US0D1021737S

(12) **United States Design Patent** (10) Patent No.: **US D1,021,737 S**
(45) Date of Patent: ** Apr. 9, 2024

(54) **VEHICLE WHEEL**

(71) Applicant: **Toyota Motor North America, Inc.**,
Plano, TX (US)

(72) Inventors: **Alberto Echazabal**, Prosper, TX (US);
Jakin C. Wilson, Prosper, TX (US)

(73) Assignee: **Toyota Motor North America, Inc.**,
Plano, TX (US)

(**) Term: **15 Years**

(21) Appl. No.: **29/824,123**

(22) Filed: **Jan. 21, 2022**

Related U.S. Application Data

(63) Continuation of application No. 29/721,475, filed on
Jan. 21, 2020, now Pat. No. Des. 944,707.

(57) **CLAIM**

The ornamental design for a vehicle wheel, as shown and described.

DESCRIPTION

FIG. 1 is a front perspective view of a vehicle wheel showing our new design;

FIG. 2 is a rear perspective view thereof;

FIG. 3 is a front view thereof;

FIG. 4 is a rear view thereof; and,

FIG. 5 is a side view thereof.

The broken lines in the drawings depict portions of the vehicle wheel that form no part of the claimed design. The dot-dashed lines are included for the purpose of illustrating boundary lines and form no part of the claimed design.

1 Claim, 5 Drawing Sheets
